CLAIM

The ornamental design for a tattoo applicator, as shown and described.

DESCRIPTION

FIG. 1 is a front, top and right side perspective view of a tattoo applicator showing our design;

FIG. 2 is a right side elevation of the tattoo gun of FIG. 1;

FIG. 3 is a front end elevation of the tattoo gun of FIG. 1;

FIG. 4 is a left side elevation of the tattoo gun of FIG. 1;

FIG. 5 is a rear end elevation of the tattoo gun of FIG. 1; and, FIG. 6 is a top plan view of the tattoo gun of FIG. 1.

Broken lines through out the figures form no part of the claimed design but rather are simply provided to show the environment.
